UNITED STATES PATENT OFFICE.

EMIL JAGENBERG, OF DÜSSELDORF, GERMANY.

MACHINE FOR MAKING PAPER BOXES.

1,021,315.

Specification of Letters Patent. Patented Mar. 26, 1912.

Application filed October 5, 1910. Serial No. 585,348.

To all whom it may concern:

Be it known that I, EMIL JAGENBERG, a citizen of the German Empire, and a resident of Dusseldorf, Germany, have invented 5 certain new and useful Improvements in Machines for Making Paper Boxes, of which the following is a specification.

This invention relates to a machine for making paper boxes such as are used for holding chocolates, cigarettes or other articles.

The machine receives a blank provided with a first pair of rear lateral flaps, and a second pair of front lateral flaps. Of these, 15 the rear flaps are first folded, then the blank is doubled, and then the front flaps are folded and pasted to the rear flaps. In this way the box is completed in a quick and simple manner, while the finished product 20 is free from all wrinkles or objectionable bulges and presents a true rectilinear contour.

In the accompanying drawing: Figure 1 is a longitudinal section of the left end of a 25 machine embodying my invention; Fig. 1^a a similar view of the right end; Fig. 2 a plan; Figs. 3-6 represent the blank in consecutive stages of formation.

The blank 1 when introduced into the machine has the form indicated in Fig. 3, being provided at each side with two laterally extending flaps, set off from the ends, while the blank is scored along the dotted lines. A stack of these blanks is placed into a 35 magazine 2 in advance of a plunger 3, which is pressed against the blanks by a weight 4 and in turn presses the blanks against a conveyer band 5 preferably made of rubber. Between the base plate 6 of the magazine 40 and the band 5 is formed a slit of a width to permit the passage of a single blank only. Band 5 receives its motion from a shaft 7, which by chain 8 drives a shaft 9. The latter, by toothed segment 10 and pinion 11 45 intermittently rotates a shaft 12, which carries the driving pulley of band 5. At each movement the band will take along a blank 1 and convey it between a pair of feed rollers 13 which are composed of rubber, or are 50 coated therewith. To prevent that during this movement, a second blank is taken along, there is mounted in front of the stack, a resilient stop 14, which during the descent of the foremost blank, clears the same, and 55 bears against the succeeding blank. Rollers

13 are driven from shaft 9 by suitable gear transmission and feed the blank into a chute 15, within which it slips against a conveyer band 16. The latter is guided over sprocket wheels 17, 18 of which wheel 17 is continuously driven from a shaft 19 by gear wheels 20. The teeth 21 of the sprocket wheels enter corresponding apertures 22 of band 16, so as to prevent slipping.

Band 16 carries a number of uniformly 65 spaced plates or cores 23, each of which is secured to the band in proximity to one of its transverse edges, so that the core will always assume a tangential position to the band. In this way the plates will during 70 the rotation of the band be held off the same at their forward end (Fig. 1). Thus the blank descending in chute 15, will fall behind one of the plates, and upon a laterally extending projection or pin 24, so that the 75 blank will be taken along by the plate.

Above band 16 are arranged a pair of spaced folders 25 that are adapted to straddle the core and terminate at their forward end in proximity to the tangential line at 80 which the band parts from the front wheel 17. Folders 25 have inclined upper faces over which the front flaps *y* of the blank will freely glide, while the rear flaps *y'* will, by core 23 be forced against the inner 85 working faces of the folders, so as to be turned upward as illustrated in Fig. 4. Back of folders 25 are yieldingly journaled a plurality of rubber or rubber coated rollers 26. Furthermore there are arranged 90 sidewise of conveyer 16, rotatable disks 27 that dip into a receptacle 28 containing an adhesive and are driven from shaft 7. Above disks 27 are yieldingly hung rollers 28^a.

The blank is so located relatively to plates 23, that the forward edges of the latter are aligned with the crease X of the former. If now during the further movement of the blank, its forward upwardly deflected end is forced against and below rollers 26, such end 95 will be bent over the plates (Fig. 5) and be pressed tightly against the same. During this movement the flaps *y* will pass along the gumming disks 27, against which they are pressed by rollers 28^a so that the flaps 100 are gummed at their inner sides. Back of rollers 26, is arranged a second set of folders 29, that gradually bend front flaps *y* downward and against flaps *y'*. Sidewise 105 of conveyer 16 are fitted yielding rails 31, 110

carrying rollers 32, and pressing with said rollers against the blank fed therebetween. In this way, flaps *y* will be so held against flaps *y'*, that they will become pasted there-
 5 to in a reliable manner and without forming wrinkles. Furthermore there are mounted above conveyer 16 a number of vertically yielding rollers 33, that firmly press the blanks against plates 23, so that the box
 10 will not bulge, and will receive an exact rectilinear shape. Back of disk 18, are hung a pair of levers 34, carrying at their forward end a shoe 42, provided with pins or projections. Levers 34 are spring-pressed
 15 against adjustable abutments 35 (Fig. 1) and are fulcrumed to a lever 36 influenced by spring 37.

To the shaft of lever 36 is secured an arm 38, linked to a rod 39, which is operated by
 20 cam 40. The shaft of this cam is operated from shaft 45 of sprocket wheel 18, by a gear transmission. By the means described, lever 36 is advanced against action of spring
 25 37, at the moment a box arrives within reach of arms 34. In this way shoe 42 is projected against the box to move it downwardly out of engagement with plate
 30 23, the latter being provided with grooves 41 for accommodating the projections of the shoe. As levers 34 are spring-mounted, they can yield together with the shoe, such yielding being necessary owing to the fact that while plates 23 are rectilinear, levers 34 turn in the arc of a circle. The box stripped
 35 off plates 23, falls into a hopper 43, having a lower egress opening which permits a single box to pass snugly therethrough. In this way the box drops in an upright position upon an endless transport band 44, op-
 40 erated by shaft 45 and carrying the box back toward the forward end of the machine. The movement of band 44 should be so slow, that the boxes will be supported upon the same, in close proximity to each
 45 other, so that several boxes may be simultaneously grasped and removed by hand. In place of levers 34, 36, a differently constructed stripping device may obviously be employed, such as a number of continuously
 50 rotating arms that liberate the box from the plates.

I claim:

1. A machine of the character described, comprising an endless conveyer, a front wheel and a rear wheel supporting the same, a core secured to the conveyer in proximity to one of the transverse core-edges, so as to be deflected from the conveyer at the wheels and to form a pocket for a box blank having laterally extending front and rear flaps, and a pair of spaced folders adapted to straddle the core and terminating at their forward end in proximity to the parting line between the conveyer and the front wheel, said folders having inclined upper faces, whereby

the front flaps of the blank will glide over the folders, while the rear flaps will be turned up thereby.

2. A machine of the character described, comprising an endless conveyer, a front wheel and a rear wheel supporting the same, a core secured to the conveyer in proximity to one of the transverse core-edges, so as to be deflected from the conveyer at the wheels and to form a pocket for a box blank having laterally extending front and rear flaps, 70 a pair of spaced folders adapted to straddle the core and terminating at their forward end in proximity to the parting line between the conveyer and the front wheel, said folders having inclined upper faces, whereby the front flaps of the blank will glide over the folders, while the rear flaps will be turned up thereby, and a plurality of yieldingly mounted rollers arranged above the 80 conveyer back of said folders and adapted to turn the forward section of the blank over the core. 85

3. A machine of the character described, comprising an endless conveyer, a front wheel and a rear wheel supporting the same, a core secured to the conveyer in proximity to one of the transverse core-edges, so as to be deflected from the conveyer at the wheels and to form a pocket for a box blank having laterally extending front and rear flaps, 90 a pair of spaced folders adapted to straddle the core and terminating at their forward end in proximity to the parting line between the conveyer and the front wheel, said folders having inclined upper faces, whereby the front flaps of the blank will glide over the folders, while the rear flaps will be turned up thereby, and a plurality of yieldingly mounted rollers arranged above the 95 conveyer back of said folders and adapted to turn the forward section of the blank over the core, 100 and to turn the front flaps against the rear flaps. 105

4. A machine of the character described, comprising an endless conveyer, a front wheel and a rear wheel supporting the same, a core secured to the conveyer in proximity to one of the transverse core-edges, so as to be deflected from the conveyer at the wheels and to form a pocket for a box blank having laterally extending front and rear flaps, a pair of spaced folders adapted to straddle the core and terminating at their forward end in proximity to the parting line between the conveyer and the front wheel, said 115 folders having inclined upper faces, whereby the front flaps of the blank will glide over the folders, while the rear flaps will be turned up thereby, and a plurality of yieldingly mounted rollers arranged above the 120 conveyer back of said folders and adapted to turn the forward section of the blank over the core, 125 and a pair of additional folders arranged back of the rollers and adapted to turn the front flaps against the rear flaps. 130

of the rollers and adapted to turn the front flaps against the rear flaps, and a plurality of pressure rollers arranged back of the additional folders, and adapted to press the top of the folded blank against the core.

5. A machine of the character described, comprising an endless conveyer, a front wheel and a rear wheel supporting the same, a core secured to the conveyer in proximity to one of the transverse core-edges, so as to be deflected from the conveyer at the wheels and to form a pocket for a box blank having laterally extending front and rear flaps, a pair of spaced folders adapted to straddle the core and terminating at their forward end in proximity to the parting line between the conveyer and the front wheel, said

folders having inclined upper faces, whereby the front flaps of the blank will glide over the folders, while the rear flaps will be 20 turned up thereby, a plurality of yieldingly mounted rollers arranged above the conveyer back of said folders and adapted to turn the forward section of the blank over the core, a pair of additional folders arranged back 25 of the rollers and adapted to turn the front flaps against the rear flaps, and stripping means arranged in proximity to the rear conveyer wheel and adapted to draw the folded blank off the core.
